UNITED STATES PATENT OFFICE.

CHARLES FRANCIS JENKINS, OF WASHINGTON, DISTRICT OF COLUMBIA.

FOLDING BOX.

941,256.

Specification of Letters Patent. Patented Nov. 23, 1909.

Application filed January 26, 1909. Serial No. 474,217.

To all whom it may concern:

Be it known that I, CHARLES FRANCIS JENKINS, citizen of the United States, residing at Washington, in the District of Columbia, have invented certain new and useful Improvements in Folding Boxes, of which the following is a specification, reference being had therein to the accompanying drawing.

10 This invention relates particularly to collapsible boxes having walls stiff enough to protect frangible or fragile articles of merchandise, and the general objects are to provide at low cost a convenient and unusually 15 rigid box without detachable parts which when collapsed may lie flat; which may be conveniently and quickly changed from its collapsible condition into box form; and which when so changed may be closed and 20 sealed as readily as a letter envelop.

The material of the box is not invariable, and certain changes may be made in construction, but for the purpose of illustration I have shown a box having two ends, or 25 smaller walls, simple plane plates and the remaining walls of stock made by securing plane paper sheets upon both faces of a sheet of corrugated paper, each of these constituent layers being of a thickness corresponding 30 to the strength desired.

In the accompanying drawings: Figure 1 is a plan view of the box structure in flat form. Fig. 2 is a section on the line 2—2, Fig. 1. Fig. 3 is a cross section of the 35 formed box, with its cover partly open. Fig. 4 is a like view, the box being closed and sealed.

In these views, A represents a sheet or layer of paper of a width equal to the length 40 of the desired box, and of a length equal to the circumference of the completed box; B, a corrugated layer of equal width and length; and C, an outer layer of the same width but having a free end or sealing flap 45 C' projecting beyond the other layers, the three layers being cemented together in the usual way.

At a short distance from each lateral edge of the compound sheet a narrow groove D, 50 parallel to the edge, is formed, preferably by sawing through or nearly through the layers A and B, and the flap C' is provided with gum C² or the like. The sheet or layer A is cut along one side of the corrugations 55 A', in which the compound sheet folds in forming the box, and when the two parts

fold the freed part V of the plane sheet covers the crevice in the angle. The portions E, E', E², E³ between the bending lines serve as the bottom, sides and top, respectively, of the box. End plates X are then inserted in the grooves at opposite ends of the section E and secured thereto by hinges F which may be of cloth or tough paper. These ends are then folded inward 65 to lie flat upon E, as in Fig. 1, and the box is ready for shipment or storage.

When the box is to be used, the ends are swung to planes perpendicular to E, their margins being thereby inserted in the grooves 70 therein, the sections E', E² are swung upward 90° to receive in their grooves the lateral margins of the ends, respectively, and the box is ready to receive its contents. The cover E³ is then folded down, bringing 75 its grooves into engagement with the upper margins of the ends, and the flap C' being moistened is drawn down and pressed upon the outer face of the section E', securely sealing the box, which obviously needs no 80 other wrappings.

It may be observed that the flap not only holds the box closed, but effectively prevents opening the box without making it evident that it has been opened. It may 85 also be noted that the ends of the box are protected by the projecting ends of the four side walls, and that the closed box bears very rough treatment without injury to the box or contents, each box being capable of 90 resisting heavy pressure or blows, even when applied diagonally. Where goods are packed in large quantities in boxes of the same size, instead of providing a stock of collapsible 95 boxes of various sizes, as is done with paper bags in retail establishments, the boxes may be made and at once filled, and in this case it is quite practicable to glue the ends in all the grooves, thereby increasing the rigidity and making it impossible to open the box 100 without seriously mutilating parts other than the flap.

Obviously the form and relative dimensions of the box may be varied without passing the limits of my invention, the terms 105 "ends" and "sides" as herein used not necessarily indicating relative size.

What I claim is:

1. A paper box consisting of a side wall member adapted to fold along parallel transverse lines to form a box body and a securing flap, and provided upon its inner face

near each of two opposite margins with a groove perpendicular to its folding lines, and end members each hinged at one side to the wall member between consecutive folding lines to swing into and out of the adjacent groove.

2. A box consisting of a side wall of four foldably connected sections, each transversely grooved near its end to receive end walls, of two end walls, each hinged to one of said sections alongside one of its grooves in position to fold flat upon the same and to swing upon an axis parallel to the groove into and out of its groove.

15 3. A paper box consisting of a side wall member made up of a sheet having substantially uniform parallel corrugations with plane sheets cemented to both faces with one plane sheet projecting at a side parallel to the corrugations to form a gummed flap, said member being grooved near its ends upon the side of the non-projecting sheet, and end members each hinged on one side to the side wall member to swing into and out 20 of the adjacent groove.

25 4. A paper box structure, adapted to lie flat, or to be folded into closed box form, consisting of a rectangular corrugated sheet faced with plane paper and grooved across

the corrugations, near each end, and two 30 end plates each hinged at one side to said sheet alongside the corresponding groove to swing upon an axis parallel thereto into and out of the same, substantially as set forth.

5. A box structure, having its body made 35 up of a corrugated sheet faced with plane paper and grooved near each end, across the corrugations, to receive end pieces, of two end plates hinged at one side to said body in position to swing into and out of the adjacent groove; one of the non-grooved sides of the body being provided with a projecting gummed flap.

6. A box body sheet made up of a corrugated sheet faced on both sides with plane 45 paper and grooved across the corrugations near each end, one facing sheet being cut along the side of certain corrugations, whereby the free portion of the cut facing sheet overlaps the angle made when the adjacent parts are folded in forming a box.

In testimony whereof I affix my signature in presence of two witnesses.

CHARLES FRANCIS JENKINS.
